US00D824304S

(12) **United States Design Patent** (10) Patent No.: **US D824,304 S**
(45) Date of Patent: **** Jul. 31, 2018**

(54) **SPOILER FOR VEHICLES**

(71) Applicant: **IGOR AKRAPOVI#**, Ljubljana (SI)
(72) Inventors: **Igor Akrapovic**, Ljubljana (SI); **Andrej Percic**, Kranj (SI); **Jure Majc**, Maribor (SI); **Luka Zagar**, Ljubljana (SI); **Uros Rosa**, Vrhnika (SI); **Bostjan Veber**, Polzela (SI)

(**) Term: **15 Years**

(21) Appl. No.: **35/502,770**

(22) Filed: **Nov. 24, 2016**

(80) **Hague Agreement Data**

Int. Filing Date: **Nov. 24, 2016**

Int. Reg. No.: **DM/095416**

Int. Reg. Date: **Nov. 24, 2016**

Int. Reg. Pub. Date: **Apr. 7, 2017**

(51) **LOC (11) Cl.** **12-08**

(52) **U.S. Cl.**

USPC **D12/181**

(58) **Field of Classification Search**

USPC D12/181

CPC B60R 13/04; B60R 13/02
